UNITED STATES PATENT OFFICE.

WILLIAM S. ELLIOTT, OF PITTSBURGH, PENNSYLVANIA.

TUBE-CLEANER.

1,036,983.

Specification of Letters Patent. Patented Aug. 27, 1912.

Application filed January 20, 1911. Serial No. 603,720.

To all whom it may concern:

Be it known that I, WILLIAM S. ELLIOTT, a resident of Pittsburgh, in the county of Allegheny and State of Pennsylvania, have invented a new and useful Improvement in Tube-Cleaners, of which the following is a full, clear, and exact description, reference being had to the accompanying drawings, forming part of this specification, in which—

10 Figure 1 is an end view of one form of tube cleaner embodying my invention; Fig. 2 is a side view of the same partly in section; Fig. 3 is a side view showing still another modification; Fig. 4 is an end view of 15 the soft metal member of Fig. 3; Fig. 5 is a longitudinal section of the same, showing the form of Figs. 1 and 2, and Fig. 6 is a form similar to Fig. 5, and showing the soft metal member of Fig. 3.

20 My invention has relation to that class of tube cleaners, wherein a cleaning tool is rotated by a motor; and the object of the invention is to provide a simple, cheap and compact tool of this type which is adapted 25 for small tubes, and which will give a rapid and efficient cleaning action upon the scale or other foreign matter in the tube.

A further object of my invention is to provide means of novel, simple and efficient 30 character for connecting the tool proper to a coupling member or carrier.

Referring to the accompanying drawings in which I have shown several different embodiments of my invention and which will 35 now be described, the numeral 2 designates the cleaning tool proper, which is of tapering form having cutting or scraping wings 3. This tool is preferably of hard metal of a character to stand the work which it is required to perform.

40 5 designates a coupling member of softer metal and which is provided with a threaded shank portion 6, by means of which it can be attached to a suitable carrier and driver, 45 such as is commonly employed with tools of this character. This coupling member is formed as shown in Figs. 6 and 7, with a plurality of radial longitudinal slots 7, corresponding to the wings 3 of the cleaning tool 50 and with a central recess 7^a. In the manufacture of the tool, the member 5 is placed in the mold in which the tool is to be formed

and the tool is cast therein, thus forming a practically integral connection between the tool members, the metal of the tool member 55 flowing into the slots 7 and recess 7^a.

In the form of my invention shown in Figs. 3 and 6, the tool member 2^b and the coupling member 5^b may be cast separately, or the part 5^b may be machined to a form 60 similar to that shown. The wings of the tool member may either be inserted in the radial slots 7^b of the coupling member and the walls of said slots swaged down on to the wings to form a secure connection between the two members, or the tool member 65 may be cast within the recess of the member 5^b.

It will be readily understood that the cleaning tool may be of various forms, and 70 that while I have shown a tool having four cutting wings or blades, the invention is equally applicable to a head having any other desired number of blades. The blades 75 may also be of any desired form, either plain or serrated.

While in Figs. 1, 2, and 5, I have shown the interior of the coupling member as having a thread or corrugation to form a secure interlock with the metal of the tool when the 80 latter is inserted therein, I desire it understood that any other suitable form of interlocking projections and recesses may be provided. The form of the coupling member may also be changed in various ways.

85 In the form shown in Figs. 1, 2, 3, 4 and 5, the portions of the coupling member between the slots 7 fit in the angles between the wings and act as reinforces therefor. It will be understood, however, that the wings 90 may be reinforced in various other ways.

I claim:

1. A tube-cleaning device, comprising a tool proper having a plurality of radial blades or wings, and a coupling member, 95 said member having a threaded shank projecting in one direction, and a hollow socket portion projecting in the opposite direction, and the tool proper having an integral anchoring portion which unites the rear ends 100 of the blades or wings and is secured within said hollow socket portion; substantially as described.

2. A tube cleaning device comprising a

2
tool and a coupling member, the coupling member comprising a threaded socket, and a hollow tool-engaging portion, the latter being larger interiorly at its inner than at its outer end and having longitudinal slots through which portions of the tool project, substantially as described.

In testimony whereof, I have hereunto set my hand.

WILLIAM S. ELLIOTT.
